UNITED STATES PATENT OFFICE.

EARL C. HANSON, OF WASHINGTON, DISTRICT OF COLUMBIA.

MUSICAL INSTRUMENT.

Application filed March 27, 1920. Serial No. 369,334.

To all whom it may concern:

Be it known that I, EARL C. HANSON, a citizen of the United States, residing at Washington, District of Columbia, have invented certain new and useful Improvements in Musical Instruments, of which the following is a specification.

My invention relates to instruments for the production of music and more particularly to electrical apparatus whereby the intensity of the music is greatly augmented to be distributed over large areas such as auditoriums, ball rooms, motion picture theatres and open air resorts.

15. The object of my invention is to provide a unit piece of musical apparatus differing in no external appearances from standard instruments and yet equipped with electrical apparatus to greatly increase the intensity 20 of the music produced.

Another object of the invention is to provide a unit piece of musical apparatus with electrical equipment included therein and adapted to be operated by connection with 25 the usual source of house lighting current. In lieu of this however a small storage battery installation may be employed.

The invention is particularly adapted for 30 phonographs to render the music produced by such machines of audibility equivalent to orchestral music. The machine therefore can be substituted for orchestras of a number of pieces and the same effects and volume 35 of music produced as now rendered by orchestras in ball rooms, auditoriums and other amusement places.

Reference is had to the accompanying drawings forming part of this application in which:

40. Figure 1 is a cross sectional view of a phonograph containing within the usual cabinet the electrical equipment.

Figure 2 is a diagrammatic view showing 45 the wiring of the apparatus within the phonograph cabinet.

Referring to Figure 1 reference numeral 1 indicates a phonograph cabinet having the driving mechanism 2 for rotating the record table 3. The usual sound box 4 is arranged for relative motion over the record and has its tone arm terminating in the telephone microphone transmitter 5 suitably supported as indicated at 6. The telephone transmitter 5 is electrically connected in circuit with the input side of the thermionic vacuum tube power amplifier indicated as con-

tained in case 9. The storage battery 11 supplies the current for the microphone circuit. The amplifier 9 derives energy for its operation from motor generator set 10 and 60 terminals 12 adapted for connection with any suitable source. The output circuit of the amplifier is connected to any suitable type of loud speaker telephone 8. The loud speaker is arranged to concentrate the sound 65 vibrations through the amplifying horn 7 from which the music is directed from the cabinet.

In Figure 2 the amplifier is shown as comprising two stages of audio frequency amplification. The vacuum tube 14 has its filament supplied with energy from alternating current mains 12 through step down transformer 18. The low potential end of the grid circuit of vacuum tube 14 is negatively 70 biased by battery 17 connected between the secondary of transformer 13 and the midpoint of the secondary winding of transformer 18. Transformer 15 is interposed in the output circuit of the vacuum tube 14 75 and the input circuit of vacuum tube 16. The tube 16 has its filament also supplied from the secondary of transformer 18 and has a negatively biased grid from battery source 17. The plate circuits of each of the 80 tubes are supplied with direct current from motor generator 10. The generator has its negative terminal connected to a variable contactor of resistance 19 bridged across the secondary circuit of transformer 18. 85 The positive terminal of the generator is 90 wired to complete the plate circuit's supply through the primary winding of transformer 15 and through the loud speaker 8 arranged in the output circuit of vacuum 95 tube 16.

The operation of the apparatus will be readily understood. The sound vibrations from sound box 4 are converted into electrical energy to the primary circuit of 100 transformer 13; said energy is amplified through the agency of the vacuum tubes 14 and 16. The load speaking telephone 8 is actuated by this greatly amplified energy producing the required volume of sound. 105

What I claim and desire to secure by Letters Patent is:

In a phonograph, the combination of a cabinet, means therein for producing music, means, including a telephone microphone 110 transmitter, for converting the musical vibrations into variations of electrical

energy, a transformer therein having a primary and secondary winding, a thermionic vacuum tube amplifier therein, the primary circuit of said transformer being energized by said variations of electrical energy, the secondary winding being associated with the input circuit of said vacuum tube amplifier, a pair of terminals for connection to a source of alternating current, a second transformer therein for supplying energy to the filaments of said vacuum tube amplifier, a direct current generator therein for energizing the plate circuits of said vacuum tube amplifier and a loud speaker arranged within said cabinet in the output circuit of the amplifier for reconstructing the electrical variations into music at greatly increased volume.

EARL C. HANSON.
